HARROW

Eugene L. Lancaster, Haskell, Tex., assignor of
one-fourth to R. C. Lowe, Haskell, Tex.

Application August 15, 1934, Serial No. 739,988

1 Claim. (Cl. 97—216)

This invention relates to harrows and an object of the invention is to provide a harrow that may be used successfully on bedded or flat ground or for crop cultivation.

5 The invention, together with its objects and advantages, will be best understood from a study of the following description taken in connection with the accompanying drawings wherein:

Figure 1 is a top plan view of the harrow embodying the features of the present invention.

Figure 2 is a detail sectional view through the harrow.

Figures 3 and 4 are detail views taken substantially on the lines 3—3 and 4—4, respectively, 15 of Figure 1.

Figure 5 is an elevational view of an arm and rack segment associated therewith.

Figure 6 is a detail view illustrating certain features of construction to be hereinafter more 20 fully referred to.

Figure 7 is a detail view taken substantially on the line 7—7 of Figure 2.

Figure 8 is a detail view taken substantially on the line 8—8 of Figure 2.

25 Figure 9 is a detail view taken at right angles to Figure 8.

Figure 10 is a detail view taken substantially on the line 10—10 of Figure 9.

Referring to the drawings by reference numerals, it will be seen that the harrow comprises 30 a suitable frame 10 having a draft tongue 11. Suitably mounted on the frame is a seat 12 for the operator.

Provided on the sides 10a of the frame 10 are 35 bearings 13 in which are bushings 14 having journaled therein shafts 15 to which are suitably secured the hubs of traction wheels 16 (see Figure 4). In this manner the frame is suitably supported by the traction wheels 16.

40 Rockably confined on the bushings 14 between the bearings 13 and the hubs of the wheels 16 are arms 17 which, at their free ends, are provided with openings 18 that accommodate a shaft 19. For driving the shaft 19 from the traction 45 wheels 16 there are provided on the ends of the shaft 19 pinion gears 20 which, as clearly shown in Figure 3, are in constant mesh with large ring gears 21 suitably mounted on the shafts 15 between the arms 17 and the hubs of the wheels 50 16. The pinions 20 and gears 21 are suitably housed in casings 22.

For placing the gears 21 in driving engagement with the shafts 15 the hubs of the gears 21 are provided with internal clutch teeth 24 with which 55 are cooperable teeth provided on clutch members

25 housed within the hubs of the gears 21. For shifting the clutch members 25 into and out of engagement with the clutch teeth 24, there are provided rods 26 that are slideable in sockets provided in the shafts 15, and the clutch members 25 are positively engaged with the rods 26 through the medium of pins 27 that operate in suitable slots provided therefor in the shafts 15 as will be clear from a study of Figures 4 and 6.

On their outer ends, the rods 26 are provided 10 with collars 28 with which are engaged shifting forks 29 pivoted to the side members 10a of the frame as at 30.

For rocking the forks 29 there are provided 15 manipulating rods or handles 31, operating in guides 32 and at one end having loop portions 33 that are suitably engaged with the upper ends of the forks 29 as will be clear from a study of Figures 1 and 4.

From the above, it will be apparent that when 20 the forks 29 are rocked to slide the rods 26 outwardly with respect to the shafts 15, the clutch members 25 are moved into engagement with the clutch teeth 24 thus providing a drive connection between the shafts 15 and the gears 21. 25 Drive from the shafts 15 is thereby transmitted through the gearing 20 and 21 to the shaft 19 for revolving the latter.

For raising and lowering the shaft 19 and parts associated therewith (and hereinafter 30 more fully referred to), there are provided on the arms 17 rack segments 34 with which mesh worms 35. The worms 35 are provided on the ends of shafts 36 journaled in suitable bearing brackets 37 provided therefor on the sides 10a 35 of the frame 10. For rotating the shafts 36 there is provided a main shaft 38 journaled in suitable bearings 39 also suitably provided on the frame 10, and at the ends thereof the shaft 38 is in driving engagement with the shafts 36 through 40 the medium of suitable gearing arranged in gear cases 40.

For operating the shaft 38 there is provided a shaft 41 journaled in suitable bearing brackets 42 and shaft 41 is in driving engagement with the shaft 38 through the medium of suitable 45 gearing 43. For rotating the shaft 41 the same is provided with a hand wheel 44 and for releasably securing the hand wheel against accidental rotation, there is provided a suitably mounted pivoted locking member 45 that is adapted to engage with the wheel in a manner clearly suggested in Figures 1 and 2.

Manifestly by rotating the wheel 44 drive is transmitted from the shaft 41 to the shaft 38 55

and from the shaft 38 to the shafts 36, and by reason of the worms 35 engaging the segments 34, arms 17 will be caused to rotate about the bushings 14 as axes to raise or lower the shaft 19 as may be found desirable.

Mounted on the shaft 19 is a harrow assembly which, in the present instance consists of a pair of spaced spider members 46 that support therebetween a circular series of rods 47 the ends of 10 which are rotatably received in suitable openings provided in the rims of the members 46. The members 46 have their hubs secured to the shaft 19 in any suitable manner to rotate with said shaft.

15 Carried by each rod 47 is a series of relatively spaced harrow fingers 48 and each harrow finger 48 is secured to its rod 47 through the medium of a suitably apertured U-shaped clamp 49 provided with a screw 50 that serves to secure the 20 clamp 49 in position and the finger 48 secured at the desired angle between the rod 47 and the inner end of the screw 50 (see Figure 7).

From the above it will be seen that the fingers 48 are so mounted that, in the event one or more 25 of the fingers come into engagement with an obstruction, the associated rod 47 will rotate in the proper direction to release the finger and thus prevent breaking thereof.

To return the rod 47 to its normal position 30 upon movement of a finger or fingers 48 out of engagement with such an obstruction as above alluded to, each rod 47 is provided at one end thereof with a suitably shaped plate 52 that is secured to the rod 47 in any suitable manner 35 such as by a set screw or the like 52'. Rotative movement of the member 52 and associated rod 47 is limited through the medium of a headed stud 53 provided on an adjacent spoke 46a of the spider and operating in an arcuate groove 54 40 provided in the plate 51. Also mounted on the same spoke of the spider is a bracket member 55 to which is pivoted one corner of a substantially triangular plate 56 as at 57. At the apex thereof, the plate 56 is pivoted as at 58 to one 45 end of a bifurcated link 55, the legs of which straddle the plate 52.

The link 55 is connected with the plate 51 through the medium of a bolt 59 that is engaged in openings provided in the legs of the link 55 50 and which operates in the slot 54 of the plate as will be clear from a study of Figures 9 and 10.

As shown in the last named figure (10), the bolt 59 is provided on one end with a nut 60 having a reduced cylindrical portion for accommodating the opening in one of the legs of the link 55 while at the head end thereof the other leg of the link 55 is arranged between the head of the bolt and a suitable shoulder 61 provided thereon. Preferably, and as shown, the plate 51 at opposite sides thereof and at the edges of the slot 54 55 is suitably roughened to prevent undue slippage of the bolt 59.

For yieldably retaining the parts in the positions shown in Figures 8 and 9, there is provided

a suitable spring device which includes a shank member 62 that has portions thereof straddling the plate 56 and pivoted to the bracket 55 as at 63. Slidable on the shank member 62 is a plate 64 that is provided with ribs adapted to engage a selected one of two or more notches 65 provided in an edge of the plate 56. A spring 66 is disposed on the shank 62 between the aforementioned plate 64 and a nut 67 and this spring serves to urge the plate 64 upwardly to engage the ribs thereof with the selected notch 65.

For limiting the movement of the link 55 the latter is provided with an adjustment screw 68 that has one end adapted to abut the adjacent spoke 46a as shown in Figure 9.

It will be understood that normally the parts are in the positions suggested in Figures 8 and 9. Should one of the fingers 48 strike an obstruction to cause the associated rod 47 to rotate, in a clockwise direction as viewed from Figure 10, the plate 51 will rotate in a corresponding direction causing a downward push on the link 55 which will result in the plate 56 being caused also to rotate in a clockwise direction. After the finger has passed over the obstruction, spring 66 will act on the plate 56 to return the parts to the normal position or the position shown in Figure 10.

If desirable, and as shown, a suitable shield 67 may be provided for the harrow finger assembly and the shield is transversely curved, and extends 30 longitudinally of said assembly, and is properly supported in operative position to the assembly through the medium of brackets or supporting means 68.

In actual practice, the harrow finger assembly 35 is driven from the wheels 16 by placing the clutch members 25 in engagement with the clutch teeth 24 of the gears 21 as hereinbefore set out. When it is desired to raise or lower the harrow finger assembly relative to the ground for controlling 40 the digging depth of the fingers 48, the wheel 44 is rotated in order, through the mechanism hereinbefore described, to rock the arms 17.

What is claimed is:

A toothed cylinder for harrows comprising a 45 shaft, spiders mounted on said shaft, a circular series of rods rotatably supported by said spiders, a series of relatively spaced harrow fingers mounted on each rod to rotate therewith, and yieldable devices connected with the rods to normally urge the rods to rotate in one direction, said rods being rotatable in a reverse direction upon impact of a harrow finger with an obstruction, each of said devices including a member secured to a rod for rotation therewith and provided with an arcuate slot, a bracket member fixed relative to the rod, a plate pivoted to the bracket member, a link pivoted to the plate, a bolt carried by said link and operating in said slot, and a spring device engaged with the bracket and said plate, yieldably retaining the plate in a predetermined position.

EUGENE L. LANCASTER.
